UNITED STATES PATENT OFFICE.

JOHN S. CRAWFORD, OF NEW LONDON, CONNECTICUT.

TRAIN-CONTROL APPARATUS.

1,391,941.

Specification of Letters Patent. Patented Sept. 27, 1921.

Original application filed December 26, 1917, Serial No. 208,779, Patent No. 1,362,927, dated December 21, 1920. Divided and this application filed December 21, 1920. Serial No. 432,182.

To all whom it may concern:

Be it known that I, JOHN S. CRAWFORD, a citizen of the United States of America, residing at New London, in the county of New London, Connecticut, have invented a new and useful Train-Control Apparatus, of which the following is a specification.

This application is a division of my co-pending application, Serial No. 208,779, filed December 26, 1917, which has now matured into Patent 1,362,927, Dec. 21, 1920, for automatic train control, and relates to the automatic control of railway trains, and has for its objects the provision of reliable and efficient mechanism for automatically controlling a train in the presence of danger conditions.

The invention of my aforesaid application is designed to be applied to and used in conjunction with the usual air brake systems and briefly stated comprises a control valve adapted to be operated by a so-called "cam" or obstruction provided on the trackway and which when so actuated permits pressure from the train pipe to actuate a valve for shutting off communication between the main reservoir and engineer's valve, said train pipe air being thereby vented to bring about an application of the brakes. This shut-off valve when so actuated serves to open up a flow of fluid under pressure from the main reservoir to a pressure operated power controlling member, and also provides for a flow of actuating fluid to restore the control valve to its original condition.

The particular invention to be covered in this application relates to the trackage arrangement or electromotor and signal system for operating the control valve.

Other features of the invention will appear as the specification proceeds, attention being now directed to the accompanying drawings which illustrate the invention embodied in a practical working form.

In said drawings:—

Figure 1 is a more or less diagrammatic representation of my automatic control system as applied to a steam railway, the several parts of the apparatus being for the most part shown in section to better illustrate their construction and operation.

Fig. 2 is a cross sectional view of the service and emergency control valves.

Fig. 3 is a sectional view of the same valves as shown in Fig. 2, but taken in a plane at right angles to that of Fig. 2.

Fig. 4 is a sectional detail view of a swivel joint.

Fig. 5 is a sectional view showing the throttle latch releasing means; and

Fig. 6 is a fragmentary sectional view of a part of a compensating or automatically adjusting valve.

The numeral 7 designates the train pipe or train line of a typical air brake installation, 8 indicating the main reservoir and 9 the engineer's valve of such system, said engineer's valve being disposed as usual in a pipe connection 10 between the main reservoir and train pipe. 11 designates the power controlling member, which in the case of a steam railway is illustrated in the form of a throttle lever.

The control valve is indicated at 12 and the shut-off valve is indicated at 13.

Specifically the control valve comprises in the present disclosure a cylinder 14 within which there is mounted a valve piston 15 controlling an inlet 16 and an outlet 17, said piston being mounted on a protruding piston rod 18 carrying a roller 19 at its lower end for engagement with the track cam. This latter element is designated 20 and may be in the form of a short rail section or ramp disposed between the tracks in position to engage when raised with the trip roller 19.

The cam or tripping device is actuated in the present illustration by an electric motor comprising an armature element 21 mounted on a vertically reciprocating plunger 22 and working within a relatively stationary field magnet structure 23. The cam is mounted on the upper end of the plunger 22 and this vertically reciprocating structure may be counter-balanced by a weight 24 adjustably engaged on the end of a pivoted lever 25 which is shown pivotally engaged with the lower end of the plunger. The electrical connections, as will later be pointed out in detail, are such that at one time the armature and field will be energized to attract one another and under reverse conditions will be energized to repel each other.

The main shut-off valve 13, as here disclosed, consists of a cylinder 26 within which works a piston 27 carrying a valve 28 for

engagement with a valve seat 29, the latter being disposed in a passage forming part of the connections between the main reservoir and engineer's valve.

5 The shut-off valve piston 27 also controls a vent 30 to atmosphere.

The control or trip operated valve is connected at its inlet side 16 by piping 31 with the train pipe and is connected at its outlet 10 side 17 by piping 32 with the cylinder 26 of the shut-off valve.

From the construction thus far described it will be apparent that when the trip roller on the controller valve encounters the 15 raised cam 20, said valve will be lifted, upwardly opening communication between the inlet and outlet ports 16—17 and permitting a flow of air from the train pipe through pipe 32 to the head of the actuating piston 20 27 of the shut-off valve. This piston will be thereupon actuated to carry the valve 28 to its seat thereby cutting off communication between the main reservoir and engineer's valve. The piston in this movement 25 covers the vent 30 thereby permitting the train pipe air to escape by way of said vent, this resulting in an application of the brakes.

The force for cutting off the steam or other power is supplied in my present disclosure from the main reservoir through 30 pipe 33 by-passed around the shut-off valve and under the control of a valve 34 which in turn is under the control of the shut-off valve. This air supply valve 34 is shown 35 directly connected with a piston 35 working in a cylinder 36 which latter may be made as an integral part of the main shut-off valve. The top of cylinder 36 above the head of the piston therein is connected by 40 a port 37 with the shut-off valve passage 38 so that when the shut-off valve is open, as it is under normal running conditions valve 34 will be held closed by the main reservoir 45 pressure on top of piston 35. When however the shut-off valve is actuated as above described, to close off communication between the main reservoir and engineer's valve, the port 37 will be covered by the stem portion 39 of valve 28 and pressure on top 50 of piston 35 will be thereby removed. The remaining pressure on top of piston 35 is vented at such times by way of a vent port 40 provided in the cylinder above the piston and connected by piping 41 with a port 42 55 opening into the cylinder 26. This port 42 is normally covered by the piston 27 but when said piston is moved over as above described to close the shut-off valve, said port is opened and the pressure on top of cylinder 35 can thereby escape through piping 41 and port 42 out the then-opened vent 30.

When the shut-off valve has been closed and the pressure on top of piston 35 thus 60 relieved, the air supply valve 34 opens under

influence of the main reservoir pressure supply beneath the same through piping 33 and permits flow of air at said reservoir pressure through port 43 and by way of piping 44 to a point beneath the piston 45 70 in the throttle closing cylinder 46. This piston is connected by a piston rod 47 with the rearward end of the pivoted throttle lever so as to impart a closing movement to the throttle. 75

To enable this closing movement the throttle latch must be released and this is accomplished in the case illustrated by a throttle lifting piston 48 connected with the latch rod 49 and working in a cylinder 50, 80 said cylinder being supplied with actuating fluid through branch piping 51 connected with the supply pipe 44. A swivel joint is provided in this branch line to allow for the pivoting movement of the throttle lever, said 85 joint comprising a chambered member 52 mounted on the throttle, to which the piping leading to the latch lifting cylinder is connected and which is provided with a passage 53 concentric with the pivotal axis of the 90 throttle in which is rotatably engaged the end of the branch piping 51 leading from the supply pipe 44.

In the present illustration the control is 95 exercised from the track signals by means of switches operated by the semaphore arm and controlling operation of the cam lifting motor. 54 designates the semaphore or track signal carrying a control arm 55 supporting a series of switch contacts 56, 57 and 58 100 for bridging contacts 59—60; 61—62; 63—64 respectively. Contact 59 is connected by wiring 65 with the contact 66 within the housing 67 of the track motor, said contact being slidably engaged by a brush 68 carried by the movable element of the motor and connected by wiring 69 with the armature 21. Contact 60 is connected by wiring 70 with one side of the stationary field winding 23 and contact 61 is connected by wiring 71 with the other side of this field winding. Contact 62 is connected by wiring 72 with one of the current supplying wires 73. Contact 63 is connected by wiring 74 with a contact 75 with which engages the sliding contact 76, connected with the other side of the armature. Contact 64 is connected by wiring 77 with the other line wire 78. 110 115

When therefore the semaphore arm stands in the warning position shown in Fig. 1, the 120 circuits will be established as follows: from line wire 73 through wiring 72, contact 62, bridging contact 57, contact 61, wiring 71 through field winding 23 and by way of wiring 70 to contact 60, bridging contact 56, 125 contact 59, wiring 65, contact 66, brush 68 and wiring 69 to the movable armature windings 21 (diagrammatically shown) and thence by connection 79, brush 76, contact 75, wiring 74 to contact 63, bridging contact 130

58, contact 64 and connection 77 to the other line wire 78. These connections are such as to cause the armature and field to repel each other and the cam to be therefore raised into the tripping position indicated.

When the track signal drops back to the "safety" position circuits are established as follows for effecting a reverse operation of the motor; bridging contacts 80, 81, 82 on 10 the semaphore operated arm 55 connect contacts 83-84; 85-86 and 87-88 respectively. Under such conditions current flows from the line wire 73 through wiring 89 to contact 86 across bridging contact 81 to contact 85 15 and thence by wiring 90-71 to the first side of field winding 23, and by way of wiring 70-91 to contact 84 across bridging contact 80 to contact 83 and by way of wiring 92-74, contact 75, brush 76 and connection 20 79 to the opposite or reverse side of the armature 21 and thence by wiring 69, brush 68, contact 66 and wiring 65-93 to contact 87 and across bridging contact 82 to contact 88 and thence by wiring 94 to the return side 25 78 of the line. Under these so-called safety conditions the armature and field will attract each other and hence the cam will be lowered to an inactive position. The counter-balance weight 24 is usually so adjusted 30 that in case of any electrical connections being broken, the cam will be automatically elevated.

The control valve 12 is designed to effect a service application of the brakes. When 35 therefore said valve is operated by the cam elevated as just described, said valve will release the train pipe air at a rate such as to effect a so-called service brake application. This is accomplished by providing what I 40 have termed a compensating or automatically adjusting valve 95 in the air connections between the train pipe and control valve. This compensating valve comprises a piston 96 working in the cylinder 97 and 45 normally acted upon by the train pipe air, said piston carrying a slide 98 having a substantially diamond-shaped valve port 99 therein controlling a port 100 connected by the piping 31 with the control valve. When 50 the full pressure train pipe air is upon piston 96, the piston will be forced downward so that the constricted upper end of the diamond-shaped valve port 99 will be disposed over the outlet port 100. Consequently, with the train pipe air at normal 55 pressure, when the control valve is actuated the escape of train pipe air by way of cylinder 26 and vent 30 will at first be restricted to prevent too sudden an application of the 60 brakes. Then, as the train pipe pressure is reduced by the venting thereof, the piston 96 in the compensating cylinder will rise under the action of the counter-balance spring 101, carrying the diamond-shaped valve slide up- 65 ward to more fully open the outlet port 100,

A gradual but at the same time complete application of the brakes is thus assured.

To insure the control valve being promptly returned to its original condition after it has been actuated by the trip cam, I have provided a connection 102 for supplying air under main reservoir pressure from supply pipe 44 to the head of the piston 15 of the control valve. Thus the control valve will be restored to normal operation position 75 along with the shut-off of power.

After operation of the automatic stop mechanism the engineer may regain control of his train by opening the shut-off valve to again establish communication between the 80 main reservoir and engineer's valve, this being accomplished by returning the shut-off valve to the position indicated in Fig. 1 by forcing in the handle 103 connected with the shut-off valve. When this is done air under 85 reservoir pressure is again applied to the top of piston 35 which closes the air supply valve 34. The air from the throttle unlatching cylinder and control valve cylinder 14 in this case vent back through the pipe 44, 90 port 43 and by way of an exhaust port 104 and vent pipe 105 into the cylinder 26 at 106 in front of piston 27 and thence out the vent 30.

To prevent duplication of the engineer's 95 actions the automatic stop is automatically cut out of operation when the train is properly controlled by the engineer. Thus when the engineer, observing the signals set against him, reduces speed by applying the 100 brakes, pressure in the train pipe is reduced and this effect is taken advantage of to render the automatic stopping mechanism inoperative. The means for this purpose here comprises a cut-out cylinder 107 inter- 105 posed in the line of connections between the train pipe and control valve and having a spring pressed piston 108 therein acting as a valve to control the passage 109 between said cylinder and the compensating cylinder. 110 The train pipe air, connected by piping 110 with the head of the cylinder 107 forces said piston 108 over to open up communication between the train pipe and control valve by way of port 109. When however, the pres- 115 sure in the train pipe is reduced by the engineer's application of the brakes said piston 108 is moved over by its counter-balance spring to close the port 109 and thus cut off communication between the train 120 pipe and control valve. The operation of the control valve then will have no effect upon the system. When piston 108 thus moves over under the influence of its spring to close passage 109, it also opens up a vent 125 111 permitting the escape of air from the compensating cylinder by way of cylinder 107 and a second vent 112 to atmosphere.

In addition to service stops the invention is adapted to produce a danger or emergency 130

stop when necessary. This may be accomplished by providing a second control cylinder 113 having a valve 114 therein provided with a valve rod 115 carrying a roller 116 5 on its lower end for engagement with a so-called danger or emergency stop cam. This latter cam will be off-set to one side of the service stop cam, already described, and means similar to those described in connection with the service stop cam will be provided for operating the same. The emergency stop control acts when operated to provide for a sudden release of the train pipe pressure to thus effect an emergency 10 application of the brakes. This is accomplished in the illustration by connecting cylinder 113 directly with the train pipe by a connection 117 and with the pipe 32 by connection 118, so that when said emergency 15 valve is operated the full train pipe pressure will be quickly vented by way of vent 30 of the shut-off valve.

The service and emergency stop control valves may be coupled together in a single 20 unit as indicated in Figs. 2, 3. Said valves may be separately tested before starting on a run by means of a test valve 119 which may be turned in opposite directions to provide flow through either pipe 120 or 121 to 25 lift either one of the valves, pressure being supplied for this purpose by piping 122 connected with the main reservoir. Check valves 123 may be provided in these test connections 120, 121 to prevent escape of train 30 pipe air by way of these connections when the control valves are operated by the track trips.

The track motor which I have provided is particularly simple and sturdy in construction 40 and therefore well adapted to the uses for which it is designed. There is practically only one moving part, that is, the movable armature structure and the parts are all protected within the housing shown. As 45 a further protection, the armature structure may be covered by a bell-shaped dome or hood 124 carried by the plunger 22 and covering the armature and field and the sliding electrical connections described. By adjusting 50 the weight 24 the motor may be set to operate as desired.

The invention it will be seen is capable of ready application to the train controlling and braking systems of trains now in use 55 and it will be seen that on the whole the invention comprises but relatively few and comparatively simple parts or mechanisms which are not likely to get out of order. The system furthermore is direct and positive in its action. The ability to secure both 60 service and emergency applications is of special importance. The compensating or pressure reducing mechanism used in connection with the service braking applications is highly desirable as preventing sud-

den injurious application of the brakes and an even setting of the brakes throughout the length of the train.

I claim:

1. In a device of the character described, 70 a member for operating the control valve of an automatic train stop, and a track motor for positioning said member in the path of the control valve comprising relatively movable field and armature structures, and 75 means for reversing the electrical connections through said structures to cause the same to attract or repel each other.

2. In a device of the character described, 80 a trip member for operating the control valve of an automatic train stop, a plunger supporting said trip member, an armature structure on said plunger, a field structure disposed in magnetic relation to the armature structure, and means for relatively reversing 85 the electrical connections between the armature and field structures.

3. In a device of the character described, 90 a trip member for operating the control valve of an automatic train stop, a plunger supporting said trip member, an armature structure on said plunger, a field structure disposed in magnetic relation to the armature structure, means for relatively reversing 95 the electrical connections between the armature and field structures, and traffic controlling means for controlling said electrical connections.

4. In a device of the character described, 100 a trip for actuating the control member of an automatic train stop, and a track motor for positioning said trip in the path of the control member comprising a vertically reciprocating plunger supporting the trip member, an armature on said plunger, a field 105 structure surrounding said armature, slideable electrical connections to the movable armature, means for relatively reversing the connections between the armature and field, and an adjustable counterbalance for the 110 armature structure.

5. In a device of the character described, 115 a trip for actuating the control member of an automatic train stop, and a track motor for positioning said trip in the path of the control member comprising a vertically reciprocating plunger supporting the trip member, an armature on said plunger, a field structure surrounding said armature, slideable electrical connections to the movable armature, means for relatively reversing the connections between the armature and field, an adjustable counterbalance for the armature structure, and a hood carried by the movable armature structure covering the armature 125 and the sliding connections aforesaid.

6. In a device of the character described, 130 a trip member adapted when in one position to operate the control member of a train stop, a reciprocating track motor for mov-

ing said trip member in one direction and traffic controlling means for controlling the operation of said track motor.

7. In a device of the character described, 5 a trip member adapted when in one position to operate the control member of a train stop, an electric track motor for moving said trip member, and traffic controlling means for reversing the flow of current through a

10 part of said motor.

8. In a device of the character described, 15 a trip member adapted when in one position to operate the control member of a train stop, a reciprocating track motor for moving said trip member in one direction, traffic controlling means for controlling the operation of said track motor, and means for

shielding the working parts of said track motor.

9. In a device of the character described, 20 a trip member adapted when in one position to operate the control member of a train stop, a reciprocating track motor for moving said trip member in one direction, and means for controlling the operation of 25 said motor.

10. In a device of the character described, 30 a trip member adapted when in one position to operate the control member of a train stop, a reciprocating track motor for moving said trip member in one direction, means for controlling the operation of said motor, and a counterbalance for said trip member.

JOHN S. CRAWFORD.
